Primary Examiner — Rhea Shields(74) *Attorney, Agent, or Firm* — FRESH IP PLC; Clifford D. Hyra; Aubrey Y. Chen(57) **CLAIM**

The ornamental design for a diaper, as shown and described.

DESCRIPTION

FIG. 1 is a front perspective view of a diaper;
 FIG. 2 is a cross section thereof, taken along section line 2-2.
 As only the perimeters of the channels are claimed, the side ends of the cross-section are not shown;
 FIG. 3 is a left side view thereof;

FIG. 4 is a right side view thereof;

FIG. 5 is a front view thereof; and,

FIG. 6 is a rear view thereof.

In the drawings, the broken lines are for the purpose of illustrating portions of the diaper and form no part of the claimed design.
